PROTECTIVE HOUSING FOR AN OPTICAL, RADAR AND OTHER TRACKING DEVICES

Edward L. Morgan, Asheville, N. C., assignor to Oerlikon
Tool & Arms Corporation of America, Swannanoa,
N. C., a corporation of Delaware

Application July 13, 1955, Serial No. 36,966

Term of patent 7 years

(Cl. D13—1)

FIG. 1

FIG. 2

FIG. 3

FIG. 4

Fig. 1 is a plan view of a protective housing for an optical, radar and other tracking devices embodying my new design, with the top door in fully open position;

Fig. 2 is a front elevational view of the same;

Fig. 3 is a rear elevational view of the same, and

Fig. 4 is an end elevational view of the same.

The characteristic features of my design reside in the portions shown in full lines in the drawings.

I claim:

The ornamental design for a protective housing for an optical, radar and other tracking devices, substantially as shown and described.
